JOHN E. W. FOGAL, OF QUINCY, ILLINOIS, ASSIGNOR TO QUINCY ELEVATOR GATE CO., OF QUINCY, ILLINOIS, A CORPORATION OF ILLINOIS.

ELEVATOR-DOOR-OPERATING MECHANISM.

1,201,814.

Specification of Letters Patent.

Patented Oct. 17, 1916.

Application filed April 15, 1916. Serial No. 91,317.

To all whom it may concern:

Be it known that I, JOHN E. W. FOGAL, a citizen of the United States, and a resident of Quincy, in the county of Adams and State of Illinois, have invented a new and Improved Elevator-Door-Operating Mechanism, of which the following is a full, clear, and exact description.

This invention relates to elevator well doors and has particular reference to improved means for controlling the operation thereof from the elevator car.

Among the objects of the invention is to simplify and improve the well door operating mechanism with respect not only to simplicity and reliability of operation, but also with respect to the safety afforded by the apparatus with the running of the entire equipment.

More definitely stated, I provide locking means for a series of vertically slideable well doors serving to hold the doors locked shut except when the elevator car is in position to permit one of such doors to be opened, means also being provided to prevent the operation of the car when any one of the doors is open.

With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a perspective diagrammatic view showing an elevator shaft, a series of vertically movable doors opposite their respective floors, an elevator car adapted to reciprocate up and down in the shaft, and power mechanism for operating the doors and controlling the operation of the car; Fig. 2 is a side elevation of one of the wall fixtures, a fragment of the door lifting bar guided therein, and the co-operating devices for controlling the position of the door; Fig. 3 is a similar view of the same mechanism including the push bar carried by the car and indicating its position with respect to the locking and controlling mechanism for the door when the car is adjacent thereto; Fig. 4 is a front elevation of the door con-

trolling mechanism in the position indicated in Fig. 3; and Fig. 5 is a detail view of an automatic switch controlling the operation of the car with respect to the position of the doors.

Although I show and refer herein to a series of vertically slideable well doors, I shall hereinafter employ simply the term "door" and mean thereby to cover any suitable construction of well door irrespective of its position or direction of movement so long as the spirit thereof is included within the terms of the specification and claims. By the terms "elevator car" or simply "car" I mean to cover any type of elevator vehicle for the conveyance of passengers, freight or the like, up and down in an elevator shaft.

Referring now more particularly to the drawings, I show a car 10 movable up and down in the shaft 11, guided by any suitable or well known means to prevent undue lateral vibration or movement, and adapted also to be stopped adjacent any one of a series of floors 12 of the building, the approach to which or the exit from which is guarded by a door 13. At 14 is indicated a push bar pivotally connected by a pair of links 15 to a rigid bar 16 secured to some suitable portion of the car adjacent the doorway of the shaft. A spring 17 tends to project the bar outwardly with respect to the car toward the doorway.

At 18 I show a vertical lifting bar held for movement in a definite vertical line or plane by guides 19 constituting parts of brackets 20 secured rigidly to the wall of the elevator shaft adjacent the respective doors. To each of the brackets 20 is pivoted at 21 a latch 22, the latch extending upwardly from its pivot and normally hooking or locking over the upper edge of an arm 23 extending laterally from the door 13 adjacent such bracket. A cheek plate 24 is secured to the front part of each latch substantially half way between the pivot thereof and the hook portion at its upper end. A spring 25 acts upon the latch tending to force it forwardly into locking position, but such swinging movement is limited by a lug 26 carried by the guide portion of the bracket.

A catch 27 is secured rigidly to the lifting bar 18 and carries a nose portion 28 which extends toward the bracket 20 and thence downwardly, hooking normally over the upper edge of the arm 23 on one side of the

hook portion of the latch. This catch serves not only to prevent the undesired opening movement of the door, but also to hold the door arm in the plane of the adjacent edge 5 of the lifting bar where it will be sure to be engaged by the points 29 of an operating block or actuator 30 pivoted at 31 upon a knuckle 32 secured to the lifting bar below the catch. The actuator extends upwardly 10 from its pivot and embraces both sides of the lifting bar, the side plates of the actuator being connected by a web 30' and thereby movement of the actuator laterally with respect to the plane of the lifting bar is prevented. The sides of the actuator are normally at the same level as the cheek plate 24 and are adapted to contact said cheek plate when the actuator is thrown outwardly 15 toward the bracket by action of the push bar 20 carried by the car, as shown in Fig. 3. The contact between the push bar and the actuator is borne by an anti-friction roller 33. The free edges of the sides of the actuator are long enough to cause the latch to be 25 thrown out of locking position with respect to the arm 23 and to bring the upwardly projecting points 29 of the actuator beneath and beyond the lower edge of the arm 23. When the lifting bar is lifted, therefore, the 30 actuator will securely grasp the door arm and thereby the door will be lifted with the continued movement of the lifting bar. The normal position of the actuator is toward the path of the car with the points 29 thereof 35 lying against a pin 34 extending laterally from the lifting bar. The actuator is thrown to this position by virtue of the spring 25 acting through the latch and cheek plate when the latch comes into locking position, and the actuator is maintained in such 40 normal position by the action of gravity on the weighted roller end thereof. I wish to observe at this time that each door is shown provided with two laterally projecting arms 45 23 for coöperation with locking mechanism duplicated on opposite sides of the door and with a corresponding duplication of the lifting bar. I wish it to be understood in this connection that while for simplicity of explanation I have referred hereinbefore to a 50 single locking mechanism coöperating with a single door arm, my invention is to be interpreted broadly enough to cover either one or a plurality of such devices, depending upon the specific nature of the door mechanism or the exigencies of any particular installation.

At 35 I show a motor located at any suitable place and shown as comprising a hydraulic cylinder having a piston slidably 55 therein and whose rod 36 is provided with a rack 37. Pressure fluid is admitted to the cylinder 35 by means of a pipe 38 and delivered therefrom through a pipe 39. The pipe 38 is normally closed by a valve 38^a,

and the other pipe is provided with a normally open valve 39^a. At 40 is indicated a wheel having links 38^b and 39^b extending therefrom to the valves of the respective pipes. An endless door controlling rope 41 extends up and down along the elevator shaft in position to be easily reached by the conductor of the car and is extended thence over suitable direction pulleys 42 and 43 to the wheel 40. A pull upon the controlling rope 41, therefore, will turn the wheel 40 to open the valve 38^a and close the other valve with a corresponding admission of motive fluid into the cylinder 35. The movement of the rack 37 will rotate a pinion 44 meshing therewith and such movement rotates the shaft 45 and drum 46 secured thereto. The lifting bars 18 are suspended from cables 47 which lead over suitable direction pulleys 48 and thence to said drum 46. The rotation of the drum effects a corresponding winding thereon of the cable or cables 47 and causing thereby the elevation of the lifting bars and the opening of that door adjacent which the car is located at such time, 70 all the other doors being retained in normal position in the manner and by the mechanism shown in Fig. 2. When the controlling rope 41 is drawn in the opposite direction the power devices will be restored to 75 normal position, allowing the open door to return to its closed position where it will be automatically locked and held as already described.

At 49 I show a switch box having a movable blade 50 constituting one end of a lever pivoted at 51. An anti-friction roller 52 carried on the outer free end of the lever is arranged in the path of a shoe 53 carried by a bracket clamped to the piston rod 36. When the shoe 53 moves with the piston rod, 80 in the opening of any door, the shoe bears against the roller 52 and throws the switch so as to break the circuit through the blades 54. These blades are connected to the conductor wires 55 of the main power devices (not shown) for controlling the operation of the elevator car. It will be apparent, therefore, that when any door is open by reason of the actuation of the door operating motor 35, the power will be cut off to prevent the movement of the car. When, however, the door is closed and the shoe 53 returns to its normal position, the switch 50 will again make contact between the blades, 85 restoring the operation of the main hoisting devices.

I claim:

1. The combination with a door, a lifting member movable vertically adjacent the door, and guide means for the lifting member fixed in stationary position, of an arm projecting laterally from the door adjacent the lifting member, a catch secured to the lifting member and having a nose project- 125

ing over the arm and thence downwardly, thereby holding the arm in a definite vertical plane, a latch carried by said guiding means and normally engaging over said arm 5 to hold the arm and door down, and an actuator carried by the lifting member below the catch and serving to first disconnect the latch from the arm and subsequently engage beneath the arm and lift the same 10 and the door when the lifting member is lifted.

2. The combination with the wall of an elevator shaft, a series of doors operating with respect to said wall, a bracket secured 15 to the wall adjacent each door, and a lifting member guided along all of said doors through said brackets, of an arm projecting laterally from each door adjacent the lifting member, a latch carried by each bracket 20 and engaging normally over said arm to hold the door in locked position, a catch secured to the lifting member adjacent the engaging portion of the latch and serving to prevent lateral displacement of the arm 25 from the lifting member, means acting upon the latch tending to throw it into locking engagement, and an actuator carried by the lifting member and adapted to be operated against the force of the last mentioned 30 means first to disconnect the latch from locking position and subsequently engage beneath and lift the arm and door when the lifting member is lifted.

3. The combination with an elevator door 35 having a laterally projecting arm, of a lifting bar guided for vertical movement adjacent said arm, means to prevent lateral movement of either the arm or the bar with respect to the other, an actuator movably 40 connected to the bar and lying normally at one side of the vertical plane of the arm but adapted to be thrown beneath said arm by reason of the approach of the car adjacent the door, and means to lift the bar and cause 45 the actuator to lift the arm and door.

4. The combination with an elevator door having a rigid projecting part, of a lifting bar adjacent and movable vertically along said part, means coöperating with the bar 50 and said part to prevent lateral movement of either part with respect to the other, an actuator pivotally connected to the bar and projecting upwardly from its pivot along said bar, said actuator including a weighted 55 projection serving to hold its upper end out of the path of said projecting part of the door, means carried by a car approaching the door to cause the actuator to be thrown beneath the projecting part, and means to 60 lift the bar and through it and the actuator to lift the door.

5. The combination with an elevator door and a laterally projecting arm secured thereto, of a lifting member adjacent one side 65 of the arm, a rigid fixed bracket adjacent

the door and constituting a guide for said lifting member, a catch movable vertically with the lifting member and serving to prevent lateral displacement of the arm with respect to said member, a latch pivoted to 70 the bracket and extending upwardly from its pivot for interlocking engagement with the arm to normally hold the door in locked position, an actuator secured to the lifting member below the catch, and means carried 75 by the car serving to throw the actuator against the latch to cause it to swing on its pivot and release the arm, and means to lift the lifting member.

6. The combination with an elevator door 80 and a laterally projecting arm secured thereto, of a lifting bar adjacent said arm, means to lift the bar, a bracket constituting a guide for the bar, means coöperating with the arm to hold the same and the door in normal 85 locked position, an actuator pivoted to the bar and extending upwardly from its pivot and having at its upper end a point normally at one side of the vertical plane of the arm but adapted when moved around its 90 pivot to engage beneath the arm and unlock the door, and means carried by the car to throw the actuator into its last mentioned position whereby the door will be lifted 95 when the lifting bar is lifted.

7. The combination with an elevator door and a laterally projecting arm carried thereby, of a fixed bracket adjacent the door, a lifting bar guided for vertical movement along said bracket and arm, means to lift 100 the bar to open the door, a latch pivoted at its lower end to the bracket, a spring acting upon the latch tending to cause its upper end to engage over the arm to lock the door shut, means carried by the bar and engaging 105 over the arm to prevent lateral displacement of the arm with respect to the bar, a cheek plate carried by the latch below the arm, means to positively limit the movement of the latch under the force of the spring, an 110 actuator carried by the bar and movable laterally with respect thereto, and means carried by the car coöperating with the actuator to cause such relative movement thereof against said cheek plate to release the 115 latch from the arm and subsequently engage beneath and lift the arm and door when the bar is lifted.

8. The combination with an elevator door and a laterally projecting part carried thereby, of a lifting bar, means to lift the bar, means coöperating with the projecting part aforesaid serving to hold the same in definite position with respect to the bar, an actuator pivoted at its lower end upon the bar and extending upwardly from its pivot on opposite sides of the bar and terminating in points normally below but at one side of the vertical plane of the projecting part, means carried by the bar coöperating with said 125 130

points to limit the lateral movement of the actuator in normal position, said actuator having a weighted projection serving to maintain the actuator in such normal position at one side of the plane of the projecting part, and means carried by the car coöperating with said weighted projection serving to cause the points of the actuator to move beneath the projecting part of the 10 door in position to unlock the door and subsequently lift the same during the lifting of the bar.

9. In well door operating devices for elevators, the combination with a series of 15 doors, of a vertically movable bar adjacent the doors, interlocking devices between the

doors and said bar, a power drum, a flexible connection between the bar and the drum, a fluid pressure motor including a reciprocating piston rod to rotate the drum and thereby lift the bar, a controlling rope adjacent the doors within reach of the conductor of the car to manipulate the motor, a main power cutout, and means carried by said piston rod to cut out the power to control 25 the movement of the car when any door is open.
